SADDLE SUPPORT

Ross Bull, Encino, Calif.

Application April 12, 1954, Serial No. 29,949

Term of patent 7 years

(Cl. D38—1)

To all whom it may concern:

Be it known that I, Ross Bull, a citizen of the United States and a resident of Encino, in the county of Los Angeles and State of California, have invented a new, original, and ornamental Design for a Saddle Support, of which the following is a specification, reference being had to the accompanying drawing, forming a part thereof.

Figure 1 is an elevational view showing a saddle support embodying my new design;

Figure 2 is an end view from the position indicated by line 2-2 of Figure 1;

Figure 3 is an end view from the position indicated by line 3-3 of Figure 1;

Figure 4 is a top plan view; and

Figure 5 is a sectional view taken along line 5-5 of Figure 1.

I claim:

The ornamental design for a saddle support, substantially as shown.
